CLAIM

The ornamental design for a seed cup, as shown and described.

DESCRIPTION

FIG. 1 is a perspective view of an upper cover of a seed cup shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a lower tray of the seed cup shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the seed cup where the seed cup is in a use position; and,

FIG. 18 is an enlarged view of portion 18 shown in FIG. 2. The broken lines in the drawings depict portions of the seed cup that form no part of the claimed design.
